UNITED STATES PATENT OFFICE

2,387,959

SNOWPLOW

Evert Wandscheer, Sioux Center, Iowa

Application July 14, 1941, Serial No. 402,270

1 Claim. (Cl. 37—43)

My invention relates to snow plows.

An object of my invention is to provide a snow plow which can be attached to the forward end of a truck or other heavy vehicle.

A further object of my invention is to provide a rotary cutting system having right and left hand pitches provided to move the snow to a central position, said system including blades having a partially arcuate configuration to move the snow inwardly.

A further object of my invention is to provide an opening for receiving the snow with a further fan casing for ejecting the snow.

A further object of my invention is to provide an upper snow guide shield which can be elevated as desired or moved to either side.

A further object of my invention is to provide a pair of guide blades at either side of the plow casing, which blades will co-operatively move with the steering spindles of the vehicles pushing the plow so that the blades will move in the same direction.

A further object of my invention is to provide a protecting shield which can be placed in inoperative, or operative position.

Another object of my invention is to provide disc members supporting the plow casing with said discs being at a substantial angle to the ground to prevent snow and ice gathering on the disc.

A further object of my invention is to provide cutting blades which cut uniformly into the snow from the outer extremities to the inner portions thereof.

With these and other objects in view, my invention consists in the construction, arrangement, and combination of the various parts of my device, whereby the objects contemplated are attained, as hereinafter more fully set forth, pointed out in my claim, and illustrated in the accompanying drawing, in which:

Figure 1 is a substantially isometric view of the casing and blade structure with further attached portions.

Figure 2 is a side elevation of the casing, and fan housing as attached to a vehicle,

Figure 3 is a detail of the spindle turning arrangement, and

Figure 4 is a sectional view taken through one of the blades along the lines 4—4 of Figure 1.

I have used the character 10 to designate the side walls of a semi-cylindrical casing having the semi-cylindrical rear wall 11, and journalled at 12 to either side member 10 is the horizontal shaft 13 including a central hub 14 which is at-

tached to spokes 15 which in turn are attached at 16 to the blades 17, 18, 19, and 20. The inner ends of the blades 17, 18, 19, and 20 include central portions 21 which are adapted to overlap the center of the casing, and the extreme outer edges 22 of the blades are adapted to rotate in a path lower than the lower cutting edge 23 of the casing and substantially close to the ground. The arcuate portion 11 of the casing includes the substantially oval opening 24 which communicates with a cylindrical fan housing 25 which includes the series of radially arranged fan blades 26 attached to the shaft 27 journalled within the portion 28. Hinged at 29 to the sides 10 are the vertical guide flaps 30 which include the cam portions 31 received within the cut out portions 32 of the sides 10. The portions 31 are bent out of the vertical position and at an angle thereto and are received within the forks 33 which are pivoted at 34 and extend into the arms 35 which are pivotally attached to the rods 36 which in turn are attached at 37 to arms 38 (see Figure 2) which arms are attached to shafts 39, to which shafts are attached further arms 40 which are in turn pivotally attached to the rods 41. The rods 41 are attached at 42 (see Figure 3) to the spindle arrangement of the vehicle comprising the curved bar 43 which is attached at 44, and extending from the point 44 is the arm 45 which is controlled by the rod 46 which passes to the steering arrangement of the vehicle. Movement of the rod 46 in either direction will correspondingly swing the arm 45 as well as the member 43 carrying the bar 41 forwardly or rearwardly which in turn will rock the arm 38 forwardly or rearwardly, which in turn will pivot the arm 35 about the pivot 34 which causes engagement of the fork portions 33 with the angularly inclined portions 31 so that as a result steering of the vehicle will cause the vertical side flaps 30 to move in the same direction as the vehicle is being steered.

The plow blades and fan are operated by means of a bevel gear 47 which is driven from the power take-off shaft 48 of the vehicle which bevel gear meshes with a further smaller bevel gear 49 which is attached to the long shaft 50 which is journalled within the bearing 51 which is attached at 52 to the frame 53 of the vehicle. The shaft 50 is attached to a further bevel gear which in turn meshes with the larger gear 54 supported at the front end of the vehicle which drives a shaft 55 which in turn is attached to a sprocket 56 which drives the chain 57 which drives the further sprocket 58 which is attached

to the shaft 13, the aforesaid mechanism serving to rotate the cutting blades in the direction of the arrows shown in Figure 1, it being noted from Figure 2 that the blades travel closely to the ground surface. A pair of brackets 59 are attached to the rear of the casing 11 and rotatably journaled at the end of these brackets are the disc members 60 which are at a substantial angle or about 30° from the ground plane, and which serve to support the plow and yet allow forward movement of the same, this arrangement of discs tending to be self-cleaning in that only a minor portion of the disc is in contact. This arrangement provides the feature of supporting the plow, as well as allowing forward movement of the plow and is free from ice and other obstructions. Pivottally attached at 61 to the sides 10 are the arms 62 which are attached to an upper shield member 63 having a forward up-turned lip 64 and a rearward down-turned lip 65, and beneath the same is a further arcuate shield 66 having the same shaped lips. The arcuate portion 11 of the casing also includes a forward upwardly bent lip 67. When the arm 62 is swung to a horizontal position the engagement of the lips 64 and 65 will carry the entire shield. The shield members are mutually supported, since the turned lips are concavely opposed to each other which thereby locks them together when the shield is lowered, the lip 67 serving to support both sections. The arms 62 being attached to the shield member 63, will force the inner shield member down to this position. This provides a guard for covering the cutting reel to prevent accidents and can be used to prevent ice and snow from working ahead of the reel. The outer edges 22 of the blades include the cupped inwardly turned sharpened edges 68 to provide a slicing action inwardly and to assist in conveying the snow inwardly and rearwardly to the fan. Attached to the plow casing is the bracket 69 and attached to the fan casing is the further bracket 70 in which brackets are formed the openings 71 in the angular portion 12 which portion 12 also include the gear racks 73. Engaged with the rack 73 are a pair of gears 14 attached to a shaft 75 which is attached to the deflecting housing 76. In position beneath the housing 76 are the side members 77 which are open to the fan and further members 78 including 79. By swinging the deflecting shield on its shaft to either direction the snow can be thrown to either side of the highway. Also the housing 76 can be raised to a higher position as shown

5 by the dotted figures by rotating the handle 80 which is attached to the shaft 75 which adjust the throwing height of the plow. Any suitable means can be employed to maintain the deflecting shield in position after it has been raised.

10 The fan mechanism or the shaft 27 can be driven by means of a suitable beveled gear arrangement mounted rearwardly on the fan casing 25 and driven from the shaft 55.

15 It will be noted that the blades 17 and 18 are pitched oppositely to the blades 19 and 20, such pitch being to carry the snow inwardly, so that as a result rotation of the blades in the same direction will transfer the snow to the center of the casing.

20 The pivoting of the flaps 30 allows the plow to travel efficiently and smoothly when turning inasmuch as the flaps will break away the snow ahead in the proper path.

25 It will now be seen that the entire structure functions cooperatively as the vehicle travels forwardly through the snow with the blade members carrying the snow inwardly and rearwardly through the fan housing and thence outwardly, with the flaps 30 moving in the same direction as the vehicle is steered with the disc 60 providing an efficient self-cleaning support so that the entire plow can be used in ice or snow, in restricted or wider areas, etc.

30 It will now be seen that the various advantages set forth in the objects of my invention have been achieved with the other advantages being apparent.

35 Some changes may be made in the construction and arrangement of the parts of my invention without departing from the real spirit and purpose of my invention, and it is my intention to cover by my claim any modified forms of structure or use of mechanical equivalents which may be reasonably included within their scope.

40 I claim as my invention:

45 A snow plow comprising a forward generally semi-cylindrical horizontal casing, a shaft journaled within said horizontal casing, said shaft carrying oppositely pitched spiral blades attached at either end of the shaft and passing helically toward the center of the horizontal casing, said blades being of limited width, and being spaced a substantial distance from the shaft, a fan casing 50 communicating with said generally semi-cylindrical casing, the inner ends of said blades overlapping the center of the horizontal casing.

EVERT WANDSCHEER.
